UNITED STATES PATENT OFFICE

FREDERICK WILLIAM HALL, OF LONDON, ENGLAND, ASSIGNOR TO HALL TELEPHONE
ACCESSORIES (1928) LIMITED, OF LONDON, ENGLAND, A CORPORATION OF GREAT
BRITAIN

COIN CONTROLLED VENDING MACHINE

Application filed October 11, 1928, Serial No. 311,893, and in Great Britain February 7, 1928.

The invention relates to coin-controlled vending machines, and particularly (but not exclusively) to machines for vending postage stamps, tickets and the like in strip form, the strip being fed through a delivery slot by means of a feed wheel to which rotation of predetermined extent is imparted on insertion of the prescribed coins. Generally the means for controlling the feed or delivery 5 include an escapement device, and the invention comprises improvements in such escapement devices including an arrangement whereby the escapement can be adjusted to alter the feed effected by a coin. The invention 10 comprises also means whereby a single feed device is made responsive to coins of different prescribed denominations, the feed due to each coin being proportional to the value of that coin. Further, the invention 15 comprises improvements in means for separating coins of different denominations inserted into the machine, and for rejecting improper coins.

Other improvements included in the invention 20 relate to the delivery or feed mechanism, and the actuation thereof, and to shutter mechanism for the openings through which coins are inserted, and articles are delivered.

The invention is illustrated in the accompanying drawings as applied to a machine for vending postage stamps, this machine being organized for issuing stamps of a single denomination, singly or in multiples, according to the value of the coin inserted. In describing this particular machine, reference will be had to the issue of 1-cent stamps paid for by insertion of 1-cent and 2-cent pieces.

The machine is shown in Figures 1, 2 and 3 with the casing removed.

Figure 1 is an elevation viewed from the right,

Figure 2 an elevation viewed from the left, and

Figure 3 a rear view;

Figure 4 is a horizontal section of an

escapement device included in the mechanism;

Figure 5 shows part of the mechanism, whereby the coin slot is automatically closed when the machine is empty.

Figure 6 shows a shutter and actuating mechanism therefor, whereby the stamp delivery slot is automatically closed after each delivery;

Figures 7 and 8 are two sectional views 55 of a coin detector incorporated in the mechanism, these two views being alike, but showing coins of different denominations in course of passing the detector;

Figure 9 is a vertical cross-section of the 60 stamp delivery roller, and certain parts associated therewith,

Figures 10 and 11 being views of details of this mechanism;

Figure 12 is a side elevation of another 65 form of escapement which may be used in the machine,

Figure 13 is a side elevation of an escapement of the latter form, associated with a coin transfer device to be described hereinafter; 70 and

Figures 14 and 15 are views of coin detectors which may be incorporated in the machine for specific purposes to be described hereinafter.

The frame plate 1 has near the top an opening, behind which there is a vertically slidable plate 2. This plate 2 has a coin slot, which is exposed by the aperture in the plate 1 when the plate 2 is raised, and then gives access to a coin slot in a plate 3 fixed behind the slidable plate 2. Normally the plate 2 is held in its raised position by a double armed lever 4 engaging under a lug 5 projecting 80 from the plate 2 through a slot in the plate 3, the lever being held under the lug by the action of a spring 500. At each insertion of a coin the plate 2 is slightly raised, the normally exposed part of its slot being some- 85 90

what shorter than the diameter of the coin, so that the edge of the coin lifts the plate.

Behind the plate 4 there is pivoted a heavy lever 6 having secured thereto a lug 7 facing the coin slot in the plate 3, so that by pushing a coin through this slot, against the lug 7, the lever 6 is lifted, as indicated by broken lines in Figure 1. In this figure two coins (a 1-cent piece and a 2-cent piece) are shown in broken lines, holding the lever 6 in its raised positions. The lever 6 has pivoted to it a bar 8 having a rack 9 at its lower end, whereby it engages a gear wheel 10. The latter is loose on its spindle, but is engaged with a pawl 11 pivoted to an escapement wheel 12, so that the wheel 10 can always rotate anti-clockwise, as viewed in Figure 1, but can only rotate clockwise, as indicated by the arrow, when the escapement wheel is released and can be rotated by the pawl 11. Consequently the wheel 10 retains the bar 8 and lever 6 in raised position, after insertion of the coin, till the escapement is released.

In the lowered position of the lever 6 a vertical arm 13 of this lever depresses a flange 14 on a coin selector 15 (Figures 7 and 8) suspended from an inclined spindle 16, but when the lever 6 is raised by a coin pushed past the lug 7 this coin selector swings into position to receive the coin. If a coin too small to actuate the lug 7 is inserted into the machine, the selector fails to receive it, and it drops into a refund chute. A coin which has lifted the lever 6 and been pushed past the lug 7 drops first on to a fixed coin rail 17 and then rolls down the same on to a coin rail 18 forming part of the selector. Above the rail 18 there is pivoted to the selector, at 19, a light rail 20 capable of vertical rocking movement limited by a stud 21 passing through a slot therein. This rail 20 has an inclined flange 22, channelled on its under-side, with a bend or break, so that two portions thereof are at different distances from the rail 18. If the coin on the rail 18 is a 1-cent piece it leans with its top edge against the rail 20 below the flange 22 as shown in Figure 8 and is guided by the rails 18 and 20 and a deflecting plate 220 to a vertical chute 23, into which it drops. If it is a 2-cent piece it leans against the flange 22, and is guided by this flange and the plate 220 to a vertical chute 24. If there is inserted into the machine a coin smaller than a 1-cent piece, but sufficiently large to lift the lever 6, this coin will also reach the rail 18, and will at first lean against the rail 20 below the flange 22; but below the lower portion of the flange the edge of the rail 20 is cut away so that this smaller coin will tilt over and drop through an aperture in the selector 15 into the refund chute. A coin larger than a 1-cent piece, but smaller than a 2-cent piece, will also, at the upper part of the rail 18, lean against the rail 20 below the flange 22, but on reaching the downward bend of this flange it

will lift the rail 20 and consequently lose its support, so that it also falls into the refund chute. The channelling of the under-side of the flange 22 reduces the risk of jamming in the case of coins which are only very slightly below the prescribed 2-cent size, and consequently can only just slip under the upper portion of the flange.

A 1-cent piece entering the chute 23 drops on to the bent end of the longer arm of a weighted, double armed lever 25, which extends through a slot 250 into the chute. This lever is fixed to a small rotatable drum or barrel 26, and forms part of the escapement mechanism. This barrel is close to the circumference of the escapement wheel 12, which has two parallel series of radial arms 27, the arms in the two series being staggered in relation to each other, as shown in Fig. 1, so that in effect they are disposed in pairs, side by side, but one slightly in advance of the other. Portions of the circumference of the barrel are cut away, to enable the arms 27 to clear the barrel in certain positions of the latter, but normally, when the lever or balance arm 25 is substantially horizontal, as shown in Fig. 1, the barrel is in a position in which a shoulder formed by the mutilation thereof is in the path of one of the arms 27. However, the coin dropping on to the longer arm of the lever 25 rocks this arm downwards, and rotates the barrel, so that the shoulder referred to is removed from the path of the arm 27 abutting against it. The raised lever 6, is, consequently, by means of the rack bar 8, gear wheel 10 and pawl 11 able to impart rotation to the escapement wheel 12, but this rotation is only slight, as another shoulder of the barrel is at once rocked into the path of the next arm 27 on the wheel i. e., the nearest arm belonging to the other series.

The arms 27 are fixed to the wheel by means of set screws passing through slots therein, so that the arms are radially adjustable for varying their effective length. This enables selected arms to be shortened, so that they are ineffective for checking rotation of the wheel, as they clear the barrel in all positions of the latter. Assuming, for example, that alternate pairs of arms 27 are shortened, each release of the wheel results in a rotation twice as great as if all the arms were effective.

After depressing the balance arm 25 the coin rolls off the same and drops into the till, allowing the balance arm to swing back to its normal position. By this return swing the barrel 26 is again rotated, so that the shoulder in the path of the arm 27 is removed from that path, whereby the arm is released, and is able to clear also the other shoulder, before the latter returns to the position shown in Fig. 1, in which it stops the escapement wheel when the leading arm 27 of the next pair reaches it. There being, in the example shown, six equidistant pairs of arms 27, the

1-cent piece causes the escapement wheel to make one-sixth of a revolution.

The escapement wheel 10 is connected to the stamp delivery mechanism, to be described hereinafter, and one-sixth of a revolution of this wheel is the movement required to effect delivery of one 1-cent stamp.

A 2-cent piece entering the chute 24 drops on to an upwardly directed arm 28 of the balance arm 25, this arm 28 being bent at the top to extend through a slot 29 in the chute wall. After striking this bent portion of the arm 28, as indicated by broken lines in Fig. 1, the coin depresses the arms 28 and 25, and then clears the arm 28 and comes temporarily to rest on a concave seat 30 at the bottom of the chute, this position being likewise indicated by broken lines. The depression of the arms 28 and 25 by the coin, and their subsequent release, have precisely the same effect as the depression and release of the arm 25 by a 1-cent piece, that is say the wheel 10 is allowed to make one-sixth of a revolution.

However, there extends into the chute 24, through a curved slot 31, a pin 32 projecting from a pivoted arm 33, and this arm has a flange 34, which is in the path of one of the series of arms 27 on the escapement wheel 12. In the course of the rotation of the escapement wheel due to the release of the arm 28, one of the said arms 27 strikes the flange 34, and rocks the arm 33, so that the pin 32 pushes the coin off its seat 30 through an opening in the chute wall into the chute 23.

The coin consequently drops on to the end of the balance arm 25, depressing the same, and then releasing it, whereupon the coin continues on its way to the till. This second depression and releases of the balance arm again has the effect of allowing the escapement wheel to make one-sixth of a revolution, so that another 1-cent stamp is delivered.

The feed is effected by means of a feed drum 35 having two rows of pins for engaging the perforations in the strip of stamps.

This drum is mounted on the spindle of the escapement wheel 12, and is angularly adjustable thereon, within limits, but is fixed to a collar 36 on the spindle, by means of set-screws 37 working in slots. The strip of stamps 38 is taken from a spool 39, and passes over the feed drum 35 to the delivery slot 40. This slot is normally closed by a pivoted shutter 41 (Fig. 6). A forked portion

55 of this shutter is engaged with a pin on a double-armed, spring-loaded lever 42, and this lever has a second pin 43, resting on a flange 44, which is fixed to the feed drum 35 and has notches 45, into which the pin 43 can drop, causing the shutter to be closed. At each rotation of the drum the flange 44 lifts the lever 42 and opens the shutter till a stamp has been pushed through the slot 40, the shutter being then allowed to drop back.

60 To retain the stamp strip 38 on the feed

drum 35 a segmental, floating cover 46 rests on the upper part of the drum (Fig. 9), this cover being for convenience attached to a chain, on which it hangs when removed. The cover 46 is not exactly concentric with the drum, being slightly belled out on the entrance side, so that in case the strip owing to imperfections in its perforating, tends at this part to rise from the drum, said strip will still be able to pass under the cover and will then accommodate itself to the gradually narrowing passage afforded. At the delivery end, near the slot 40, the edge of the cover is serrated (Fig. 11), to act as a cutter for the strip. To prevent the lifting of the cover by the pull exerted on the strip for cutting it, a spring 47 engages a shoulder at this end of the cover 46. Moreover, a boss on a hand lever 48 normally faces a boss 49 on the cover, but after opening the machine this lever 48 can be rocked to clear the boss 49 and at the same time to disengage the spring 47 from the cover 46, enabling the latter to be removed.

A stripper plate 50 (Figs. 9 and 10) is provided, for deflecting the free end of the strip from the drum 35 towards the delivery slot 40.

While there are stamps in the machine, and a portion of the strip 38 is taut between the spool 39 and feed drum 35, this portion of the strip passes over a pin 51 projecting from a curved, suspended lever 52 (Fig. 5), and holds this lever out of the position which it normally assumes by gravity. When the strip of stamps is exhausted the pin 51 is released, and a projection 520 on the lever 52, swinging by gravity, strikes a sliding pin 53, which it pushes against a pin projecting from the lower arm of the lever 4 hereinafter mentioned, thus rocking the upper arm away from the lug 5, which projects from the plate 2. To the lever 6 there is fixed a pin 54 which, when the lever 6 is raised, enters an aperture in the plate 2, so that even if the lever 4 has been swung out of the path of the abutment 5 the plate 2 cannot drop, and close the coin inlet, till the lever 6 has descended. The descent of the plate 2, indicating that the machine is empty, consequently does not occur till the last stamp has actually been fed to the delivery slot 40, owing to the descent of the lever 6.

For cushioning the descent of the lever 6 a dash-pot or the like may be provided.

In the modification shown in Fig. 12, the drop bar 8 actuated by the coin-operated lever engages a toothed pin wheel 55, which meshes with a pinion 56 fixed to a spindle carrying two radial arms 57, 58 in alignment with each other. The arm 57 is adjustable as to length by means of a slide tip 59, adjustable by means of a set screw. A mutilated barrel 26, substantially similar to that shown in Figs. 1 and 4, with a coin operated balance 130

arm 25 fixed thereto is so disposed that when the arm 57 is given its full length this arm, like the arm 58, is able to engage the barrel, whereas when the arm 57 is shortened it clears the barrel in all positions of the latter. Consequently one is able to arrange that when the arm 58 is released by the barrel, due to the rocking of the lever 25 by a coin, the wheel 55 and pinion 56 either rotate till the arm 57 strikes the barrel, or rotate till the arm 58 has completed a revolution, owing to the arm 57 being out of action.

Fig. 13 shows an escapement of this geared type, but without an adjustable arm, associated with a device for transferring coins from one vertical chute to the other, for producing successive actuations of the balance arm 25, as described with reference to Figs. 1 to 3. The coin transfer is effected by means of a pin 30 on a lever 33, the lever having a projection 61 in the path of two pins 60 on the hub of the arms 58.

Fig. 14 is a plan view of a device adapted for incorporation with the machine when the machine is to take coins of a prescribed diameter having central perforations. A coin 62 of this kind, having a perforation 63, is in Fig. 15 shown travelling down an inclined rail 66 as indicated by an arrow. At one side of the rail there is mounted a rotatable cross or spider 64, with arms of iron or steel, which by rotation of the spider are swung into and out of the path of the coin. A small magnet 65 is disposed above the spider, and tends to hold the spider so that one of the arms projects into the coin path and another is near the path, farther towards the coin entrance. In the position shown, the coin pushes the arm extending into its path, and tends to rotate the spider, and as the coin is of the proper diameter, with a central hole, it does rotate the spider and is able to travel on, because the arm near the path is able to enter the hole 63. If, however, a coin arrives which has not got this hole, or has not got it in the right position, the spider is unable to rotate and prevents passage of the coin, or alternatively the arm striking the side of the coin ejects the coin laterally from the chute.

Fig. 15 shows a device for preventing the passage of perforated coins. This is a pivoted arm 67 extending into the coin path, so that a coin must rotate it in order to pass. On the same pivot there is mounted a pivoted arm 68 having a hooked tip, and when the arm 67 is rotated by a coin a spring on this arm swings the arm 68 towards the coin. If the coin has no perforation the hooked tip encounters the side of the coin, but allows the coin to pass. If there is a perforation the hook enters it, and stops the coin.

It will, of course, be understood that arrangements may be made for more than two successive actuations of the delivery mecha-

nism by a single coin, and that for the purpose of successive actuations it is not necessary to transfer the coin from one chute to a chute used also by coins of another denomination.

What I claim as my invention and desire to secure by Letters Patent of the United States is:—

1. In a vending machine, the combination of two coin chutes, a delivery device for goods, an escapement controlling said delivery device and having two members extending into the respective chutes, and means whereby after actuation of the member in one of said chutes by a coin inserted thereinto the coin is automatically transferred to the other chute for actuation of the other member.

2. In a vending machine, the combination of two coin chutes for coins of different denominations, a delivery device for goods, an escapement controlling said delivery device and having two members extending into the respective chutes, and means whereby after actuation of the member in one of said chutes by a coin inserted thereinto the coin is automatically transferred to the other chute for actuation of the other member.

3. In a vending machine according to claim 1, and in which the escapement has an axle, a plurality of radial arms fixed to said axle, a rocker adapted in one position to obstruct rotation of said arms, and means enabling a selected arm or arms to be lengthened or shortened alternatively, for engaging or clearing the rocker.

4. In a vending machine according to claim 1, two circular series of rotatable radial arms on the escapement disposed in parallel planes and staggered in relation to each other, a rocker adapted in one position to obstruct rotation of said arms, and means enabling a selected arm or arms to be lengthened or shortened alternately so as to engage or clear the rocker.

5. The combination claimed in claim 1, together with a loaded actuating member for the delivery device, adapted to be stressed by the insertion of a coin.

6. The combination claimed in claim 1, together with a loaded rack, a gear wheel engaged with said rack, and a pawl and ratchet device actuated by said gear wheel for actuating the goods delivery device.

7. In a vending machine, a combination of two coin chutes, a delivery device for goods, a coin-controlled escapement controlling said delivery device and having two members extending into the respective chutes, and means actuated by said escapement whereby after actuation of the member in one of said chutes by a coin inserted thereinto the coin is transferred to the other chute for the actuation of the member therein.

8. In a vending machine the combination of a delivery device for goods, coin chute

means, an escapement adapted by a rocking movement temporarily to release said delivery device for action, and two devices actuated in succession by a coin passing through
5 said coin chute means, each adapted to impart to said escapement a rocking movement whereby temporary release of said delivery device is effected.

10 In witness whereof I have signed this specification.

FREDERICK WILLIAM HALL.
